Charles T. Grosjean, INVENTOR

UNITED STATES PATENT OFFICE.

CHARLES T. GROSJEAN, OF NEW YORK, N. Y., ASSIGNOR TO TIFFANY & CO.,
OF SAME PLACE.

DESIGN FOR A SPOON-HANDLE.

SPECIFICATION forming part of Design No. 16,560, dated March 9, 1886.

Application filed December 26, 1885. Serial No. 186,832. Term of patent 14 years.

To all whom it may concern:

Be it known that I, CHARLES T. GROSJEAN, a citizen of the United States, and a resident of the city, county, and State of New York, 5 have invented a new and original Design for a Spoon-Handle, of which the following is a specification, reference being had to the accompanying drawings, forming part thereof.

This design consists in, first, a paddle-shaped head with handle gradually swelling out toward the upper end, where it is rounded, having open-work ornaments placed on each side; second, a fine molding which incloses the form of handle, and over and across which are placed 15 at intervals a vine of leaves and bunches of grapes; third, at the heel, where the handle expands out into the bowl of the spoon, a monogram in form of a conventional Gothic ornament.

20 In the drawings, Figure 1 is a front view of a spoon containing my design thereon. Fig. 2 is a rear view thereof.

25 *a* is the form of handle, which is slender at its lower portion and widens out, as shown at *b*, at its top portion, where it contains open-work ornaments *cc*, one on each side. A fine molding, *d*, incloses this form of handle.

30 A vine of leaves, *e*, and bunches of grapes, *f*, are spread over the handle at intervals. Several quarterfoil openings, *g*, are also interspersed at intervals over the handle.

h is a conventional Gothic ornament, which

has bunches of grapes within it, forming a monogram.

This design of handle is equally applicable 35 to a fork or a knife handle.

I claim—

1. In a design for a spoon-handle, a paddle-shaped head widening out at top and containing on each side open-work ornaments *cc*, 40 substantially as shown and described.

2. In a design for a spoon-handle, a paddle-shaped head widening out at the top and containing on each side open-work ornaments *cc*, with a molding, *d*, surrounding the form, over 45 which are placed at intervals a vine of leaves, *e*, and bunches of grapes, *f*, substantially as described.

3. In a design for a spoon-handle, a conventional Gothic ornament in form of a monogram, with interspersed bunches of grapes 50 upon bowl of spoon, substantially as shown and described.

4. The design for a spoon-handle having a paddle-shaped head, open-work ornaments *cc* 55 at top, a fine molding, *d*, inclosing the form, vines of leaves, *e*, and bunches of grapes, *f*, and quarterfoil openings *g* interspersed over the same at intervals, substantially as described.

CHARLES T. GROSJEAN.
